UNITED STATES PATENT OFFICE.

ALBEN E. LUNDELL, OF NEW YORK, N. Y., AND FRANKLIN A. STEARN, OF PATERSON, NEW JERSEY, ASSIGNEES TO WESTERN ELECTRIC COMPANY, INCORPORATED, OF NEW YORK, N. Y., A CORPORATION OF NEW YORK.

TELEPHONE-EXCHANGE SYSTEM.

1,294,498.

Specification of Letters Patent. Patented Feb. 18, 1919.

Application filed November 26, 1917. Serial No. 204,081.

To all whom it may concern:

Be it known that we, ALBEN E. LUNDELL and FRANKLIN A. STEARN, citizens of the United States, residing at New York, in the 5 county of Bronx and State of New York, and at Paterson, in the county of Passaic and State of New Jersey, respectively, have invented certain new and useful Improvements in Telephone-Exchange Systems, of 9 which the following is a full, clear, concise, and exact description.

This invention relates to automatic telephone systems, and has for its object the provision of improved means for controlling the 5 disconnection of various switching devices thereof which are used for interconnecting telephone lines for conversation.

It is the object of this invention to provide improved means for controlling the 20 operation of the automatic switch mechanism or selector switches to cause their release after starting, but before completing their operation to interconnect subscribers' telephone lines.

25 The invention may readily be adapted to various types of telephone exchanges but the present embodiment is especially designed for use in semi-automatic systems wherein the sending apparatus is located at the central office and arranged for actuation by an operator in accordance with instructions received from a calling subscriber. In the system disclosed the initial connection between the operator and the calling line is made 30 by the operator by inserting a plug, at the answering end of a cord circuit, into the jack of the calling line. The outgoing end of each cord terminates in a selector switch, and sending mechanism is temporarily as- 35 sociated with the cord circuit while connection is being established, for the purpose of controlling the operation of this and other switches by means of which the connection between subscribers' lines is established.

40 These switches are of the type disclosed in Patent 1,123,696, issued Jan. 5, 1915, to E. B. Craft and J. N. Reynolds. Associated with each cord circuit and under the control of the operator, an arrangement is provided 45 whereby under certain conditions the switches which are used in establishing a connection may be returned to their normal position before a complete connection is established.

A feature of the invention is an arrangement whereby this restoring means may be operated during a period in which the selector switches are being selectively operated. 55

This feature is accomplished by holding the fundamental circuit closed upon the depression of a key by the operator, thereby causing the switch, which is being operated, to move to its uppermost position, which position is known as tell-tale. The sequence switch associated with said switch will then 60 be rotated into talking position. The switch which is being operated, is then returned to normal by the disconnection of the district selector, which is released when the tell-tale 65 position of the switch under selection is reached.

The movement of the selector mechanism may thus be checked before it has completed the desired connection and be caused immediately to return to normal. Thus in case 70 the operator has made a mistake in manipulation of the sending apparatus, she is enabled to start a new connection immediately. Heretofore, after the first selector switch had been selectively operated, the 75 connection could not be released until after the last series of impulses had been sent 80 from the sending apparatus.

In the drawing, Figure 1 shows circuits and apparatus which are directly associated 85 with a cord circuit terminating in a selector switch, this being known as the "district" switch; Fig. 2 shows the circuits associated with an incoming selector switch; Fig. 3 shows the circuits associated with a final selector switch; and Fig. 4 shows the circuits 90 associated with a sender controlling mechanism and a cord finder.

The operation of the system will now be described. First, a call will be traced from 95 a calling to a called subscriber and then the means for wiping out a call will be described. This last description will only refer to the operation of the system after one of a train of switches has been operated and is in a position to allow the operation of the remaining switches of the train, since this invention relates only to the release of the switches at this particular period of the 100 operation of the system.

When the subscriber at substation A removes his receiver from the hook, a circuit is completed from grounded battery, left-

hand winding of relay 101, outer armature and back contact of relay 102, apparatus of substation A, back contact and inner armature of relay 102, right-hand winding of relay 101, to ground. Relay 101 becomes energized and closes a circuit for lamp 103.

The operator seeing the lighted lamp inserts the plug 104 into the jack 105 associated with the calling line. A circuit is then completed from grounded battery, winding of cutoff relay 102, sleeve of jack 105, sleeve of plug 104, winding of relay 106, to ground. Relay 102 is energized and causes the deenergization of relay 101 in a well-known manner. Relay 106 becomes energized and closes a circuit from grounded battery, power magnet of sequence switch 100, upper left-hand contact of sequence switch spring 107, front contact and armature of relay 106, to ground, for moving the sequence switch 100 out of position 1 and into position 2.

In position 2, a circuit is closed from grounded battery, winding of relay 401, lower contact of sequence switch spring 402, conductor 403, left-hand contact of sequence switch spring 108, to ground. Relay 401 by attracting its left-hand armature closes a circuit from grounded battery, power magnet of sequence switch 400, upper right-hand contact of sequence switch spring 404, left-hand armature and front contact of relay 401, to ground, for moving the sequence switch 400 out of position 1 and into position 2. As soon as the sequence switch 400 reaches position 1-1/2 a locking circuit for relay 401 maintains this relay energized, this circuit being traced from grounded battery-winding of relay 401, right-hand armature and front contact of relay 401, upper contacts of sequence switch spring 402, back contact and right-hand armature of relay 405, to ground.

In position 2 of sequence switch 400, a circuit is closed from grounded battery, winding of updrive magnet 406, contact of sequence switch spring 407, front contact and left-hand armature of relay 401, to ground. Under the control of the updrive magnet 406, the brushes of the cord finder are moved upward. As soon as the brush 408 engages terminal 409, a circuit is closed from grounded battery, winding of relay 405, left-hand contact of sequence switch spring 411, brush 408, terminal 409, conductor 410, lower right-hand contact of sequence switch spring 108, to ground. Relay 405 becomes energized and closes a locking circuit for itself from grounded battery, winding of relay 405, right-hand contact of sequence switch spring 411, left-hand armature and front contact of relay 405, brush 412, terminal 413, conductor 414, upper contact of sequence switch spring 108, to ground. Relay 405 by attracting its right-hand armature

opens a branch of the energizing circuit of relay 401, but this relay is held energized until the brushes are accurately centered due to a circuit being closed from grounded battery, winding of relay 401, right-hand armature and front contact of relay 401, conductor 415, conducting segment of commutator 416, commutator brush 417, to ground. As soon as the brushes are accurately centered on the terminals, the brush 417 engages an insulated segment of the commutator 416, thus causing the relay 401 to be deenergized and open the energizing circuit of the updrive magnet 406. The deenergization of relay 401 also closes a circuit from grounded battery, power magnet of sequence switch 400, upper left-hand contact of sequence switch spring 404, back contact and left-hand armature of relay 401, to ground, for moving the sequence switch 400 out of position 2 and into position 3. In position 3, a circuit is closed from grounded battery, power magnet of sequence switch 490, lower contact of sequence switch spring 492, contact of sequence switch spring 418, to ground, for moving the sequence switch 490 out of position 1 and into position 3.

At the time relay 106 is energized, by the insertion of the plug 104 into the jack 105, a circuit is also completed from grounded battery, power magnet of listening key sequence switch 175, contact of sequence switch spring 176, front contact and armature of relay 106, to ground, for moving the listening key sequence switch out of position 1 and into position 5. As soon as the listening key sequence switch reaches position 4, the operator's telephone set is connected to the cord associated with the plug 104, thereby enabling the operator to ascertain the desired number from the calling subscriber. As soon as she obtains this number, she sets it up upon her key board. As is well known in the art, the operator has one row of office keys and four rows of digit keys, and by pressing one key of each row, six sets of impulses are transmitted due to translation. In order, however, to simplify the disclosure and description in the present invention, a key for each set of impulses is shown, it being assumed that there are two office keys instead of one.

It will be assumed that the operator depresses the No. 1 key in the office tens row, No. 2 key in the office units row, No. 0 key in the thousands row, No. 2 key in the hundreds row, No. 1 key in the tens row, and the No. 2 key in the units row. As soon as she has set up this number she depresses the start key 491, thereby completing a circuit from grounded battery, power magnet of sequence switch 400, lower left-hand contact of sequence switch spring 404, key 491, to ground, for moving sequence

switch 400 out of position 3 and into position 8. A circuit is also completed at this time from grounded battery, power magnet of sequence switch 490, upper right-hand 5 contact of sequence switch spring 492, key 491 to ground, for moving the sequence switch 490 out of position 3 and into position 6.

As soon as the sequence switch 490 reaches 10 position 6, the fundamental circuit is closed from grounded battery, winding of relay 109, lower right-hand contact of sequence switch spring 110, conductor 111, terminal 419, brush 420, right-hand armature and 15 back contact of relay 421, contact of sequence switch spring 493, outer armature and back contact of counting relay 0', winding of stepping relay 494, brush 422, terminal 423, conductor 424, upper left-hand 20 contact of sequence switch spring 112, to ground.

The relay 494 becomes energized, and by 25 attracting its armature, completes a circuit from grounded battery, winding of counting relay 1, armature and back contact of counting relay 1', conductor 497, No. 1 key of the office tens row, lower contact of sequence switch spring 496, armature and front contact of relay 494, to ground. 30 Counting relay No. 1 by attracting its armature closes a circuit from grounded battery, windings of counting relays 1 and 1', armature and front contact of counting relay 1, upper right-hand contact of sequence switch 35 spring 485, to ground. Counting relay 1', however, does not become energized at this time, due to the shunt around its winding which is closed at the armature and front contact of the stepping relay 194.

40 Relay 109 also becomes energized at the time the fundamental circuit is closed and closes a circuit from grounded battery, power magnet of sequence switch 100, lower contact of sequence switch spring 113, right-hand armature and front contact of relay 109, to ground, for moving the sequence switch 100 out of position 2 and into position 3. While the sequence switch is moving from position 2 into position 3, relay 45 109 is held energized over a locking circuit extending through its left-hand armature and front contact and the lower left-hand contact of sequence switch spring 110, to ground over the circuit previously described. In position 3 a circuit is closed 50 from grounded battery, winding of up-drive magnet 114, upper contact of sequence switch spring 115, front contact and right-hand armature of relay 109, to ground. 55 Under the control of the updrive magnet 114, the brush rod 116, carrying the line brushes 117, 118 and 119 and commutator brushes 120 and 121, is moved upward. As soon as the commutator brush 120 engages 60 the first conducting segment of the commu-

tator 122, a shunt circuit is closed around the stepping relay 494, this circuit being traced from grounded battery, winding of relay 109, left-hand armature and front contact of relay 109, lower left-hand and 70 upper right-hand contacts of sequence switch spring 110, conducting segment of commutator 122, commutator brush 120, to ground. Stepping relay 494 deenergizes and opens the shunt around the counting 75 relay 1' which becomes energized. As soon as the commutator brush 120 engages the first insulated segment of the commutator 122, the stepping relay 494 is again energized and a circuit for the 0 counting relay 80 is completed through the armature and front contact of the No. 1' counting relay. The 0 counting relay becomes energized and closes a circuit for the 0' counting relay which, however, does not become energized 85 on account of the shunt around its winding which is closed by the armature and front contact of the stepping relay 494. As soon as the commutator brush 120 engages the second conducting segment of the commutator 122, the stepping relay 494 is again deenergized thereby causing the energization 90 of the 0' counting relay. The 0' counting relay by attracting its inner armature closes a circuit from grounded battery, power 95 magnet of sequence switch 490, inner armature and front contact of the 0' counting relay, left-hand contact of sequence switch spring 485, to ground, for moving the sequence switch 490 out of position 6 and into 100 position 8. The relay 0' by attracting its outer armature opens the fundamental circuit, but the relay 109 is held energized until the commutator brush 120 engages the second insulated segment of the commutator 105 102, due to the shunt circuit previously described. As soon as the commutator brush 120 engages this insulated segment, relay 109 deenergizes and opens the circuit of the up-drive magnet 114. Brushes 117, 118 and 119 are now accurately centered upon the first set of terminals of the second group in the district terminal bank. The deenergization of relay 109 also closes a circuit from grounded battery, power magnet of 110 sequence switch 100, upper left-hand contact of sequence switch spring 113, right-hand armature and back contact of relay 109, to ground, for moving the sequence switch 100 out of position 3 and into position 6. 115 120

In position 6 a circuit is closed from grounded battery, left-hand winding of relay 123, upper right-hand and lower left-hand contacts of sequence switch spring 124, to ground. Relay 123 by attracting its outer 125 right-hand armature completes a circuit from grounded battery, power magnet of sequence switch 100, lower right-hand contact of sequence switch spring 125, outer right hand armature and front contact of relay 130

123, to ground, for moving the sequence switch 100 out of position 6 and into position 7. If the trunk with which the brushes 117, 118 and 119 are in engagement, is busy, ground 5 will be connected directly to the test terminal thereof, so that when relay 123 becomes energized it closes a locking circuit for itself from grounded battery, right-hand winding of relay 123, inner right-hand armature and 10 front contact of relay 123, conductor 126, test brush 119, test terminal 127, to ground. The relay 123 will then be energized when the sequence switch 100 reaches position 7 and a circuit will be closed from grounded 15 battery, winding of updrive magnet 114, lower contact of sequence switch spring 115, outer right-hand armature and front contact of relay 123, to ground. Under the control of the updrive magnet 114, the brushes 20 117, 118 and 119 are moved upward until the test brush 119 engages the test terminal 127 of an idle trunk, at which time the circuit through the right-hand winding of relay 123 will not receive sufficient current to 25 hold its armatures, due to the ground being connected to the test terminal through a high resistance, this circuit being traced from the test terminal 127, conductor 273, resistance 274, to ground. A circuit, however, 30 will be closed for maintaining the relay 123 energized until the brushes are accurately centered upon the terminals of this idle trunk, this circuit being traced from grounded battery, left-hand winding of relay 123, upper contacts of sequence switch spring 124, front contact and left-hand armature of relay 123, conductor 128, conducting segment of commutator 129, commutator brush 121, to ground. As soon as the brushes 35 are accurately centered the commutator brush 121 will engage an insulated segment of the commutator 129, thereby causing the retraction of the armatures of relay 123. Relay 40 123 by retracting its outer right-hand armature opens the circuit of the updrive magnet 114 and closes a circuit from grounded battery, power magnet of sequence switch 100, lower left-hand contact of sequence switch spring 125, outer right-hand armature and 45 back contact of relay 123, to ground, for moving the sequence switch 100 out of position 7 and into position 11. When the sequence switch 100 reaches position 6-1/2 and relay 123 is deenergized, ground is connected 50 directly to the test terminal 127, to cause the selected trunk to test busy at the multiple test terminals thereof, this circuit being traced from ground, upper right contact of sequence switch spring 112, inner right-hand armature and back contact of relay 123 and brush 119 to test terminal 127.

As soon as the sequence switch 100 reaches 55 position 11 and the sequence switch 490 reaches position 8, the fundamental circuit is again closed, this circuit now being traced

from grounded battery, upper contacts of sequence switch spring 201, contact 227, winding of relay 202, lower and upper left-hand contacts of sequence switch spring 203, conductor 229, resistance 228, conductor 205, 70 terminal 131, brush 117, lower contact of sequence switch spring 132, conductor 111, terminal 419, brush 420, right-hand armature and back contact of relay 421, contact of sequence switch spring 493, outer armature and back contact of counting relay 0', winding of stepping relay 494, brush 422, terminal 423, conductor 424, upper contact of sequence switch spring 133, brush 118, terminal 130, conductor 206, resistance 207, 80 upper left-hand contact of sequence switch spring 208, winding of relay 209, lower contact of sequence switch spring 210, to ground. Relays 202 and 209 are energized and close a circuit from grounded battery, 85 power magnet of sequence switch 200, lower contact of sequence switch spring 211, armature and front contact of relay 209, upper contact of sequence switch spring 212, front contact and right-hand armature of relay 90 202, to ground, for moving the sequence switch 200 out of position 1 and into position 2.

In position 2, relay 202 is still maintained energized due to a circuit being closed from 95 grounded battery, upper contacts of sequence switch spring 201, contact 227, winding of relay 202, lower right-hand contact of sequence switch spring 230, left-hand armature and front contact of relay 202, 100 upper contacts of sequence switch spring 203, to ground, over the fundamental circuit previously described. A circuit is now completed from grounded battery, winding of updrive magnet 217, lower contact of sequence switch spring 213, right-hand armature and front contact of relay 202 to ground. Under the control of the updrive magnet 217, the line brush sets and the commutator brushes 231, 232, 233 and 234 are 105 moved upward. When the fundamental circuit is closed in the manner just described, the stepping relay 494 is energized and completes a circuit from grounded battery, winding of counting relay 2, armature 115 and back contact of counting relay 2', conductor 498, No. 2 key of the office units row, upper right-hand contact of sequence switch spring 496, armature and front contact of stepping relay 494, to ground. As the commutator brush 231 moves upward, it engages the conducting segments of the commutator 235. Each time the commutator brush 231 engages one of these segments, a circuit is closed from grounded battery, upper contacts of sequence switch spring 201, contact 227, winding of relay 202, lower right-hand contact of sequence switch spring 230, left-hand armature and front contact of relay 202, conductor 246, upper contacts of 120 125 130

sequence switch spring 214, conducting segments of commutator 235, commutator brush 231, lower right-hand contact of sequence switch spring 220, to ground. This circuit 5 places a shunt around the relay 494 which deenergizes and operates the counting relays in the same manner as above described. The commutator brush 231 continues to move upward until it engages the third conducting segment, at which time the 0' counting relay will be energized. This relay by 10 attracting its inner armature completes a circuit from grounded battery, power magnet of sequence switch 490, inner armature and front contact of counting relay 0', upper 15 left-hand contact of sequence switch spring 485, to ground, for moving the sequence switch 490 out of position 8 and into position 10. As soon as the sequence switch 490 leaves position 8 the counting relays are 20 deenergized, due to the opening of their locking circuits at the upper right-hand contact of sequence switch spring 485. Counting relay 0' by attracting its outer armature opens the fundamental circuit and opens the original 25 energizing circuit of relay 202. As soon as the commutator brush 231 engages the third insulated segment of the commutator 235, relay 202 becomes deenergized and by 30 retracting its right-hand armature opens the circuit of the updrive magnet 217, and closes a circuit from grounded battery, power magnet of sequence switch 200, upper right-hand contact of sequence switch spring 211, right- 35 hand armature and back contact of relay 202, to ground, for moving the sequence switch 200 out of position 2 and into position 3.

As soon as the sequence switch 200 reaches 40 position 3 and sequence switch 490 reaches position 10, the fundamental circuit is again established, causing the energization of the relays 202 and 494. Relay 494 by attracting its armature completes a circuit from 45 grounded battery, winding of counting relay 0, conductor 499, No. 0 key of the thousands row, upper left-hand contact of sequence switch spring 496, to ground. Relay 202 by attracting its right-hand armature 50 closes a circuit from grounded battery, power magnet of sequence switch 200, upper left-hand contact of sequence switch spring 211, front contact and right-hand armature of relay 202, to ground, for moving the sequence switch 200 out of position 3 and into 55 position 4. Relay 202 by attracting its left-hand armature closes a locking circuit for itself as previously described.

In position 4 of sequence switch 200, a circuit 60 is completed from grounded battery, winding of updrive magnet 217, lower contact of sequence switch spring 213, right-hand armature and front contact of relay 202, to ground. Under the control of the 65 updrive magnet the line and commutator

brushes are again moved upward. As the brush rod 236 moves upward the third set of brushes is tripped due to the energization of the trip magnet 216, this energizing circuit being traced from grounded battery, 70 winding of trip magnet 216, upper contact of sequence switch spring 215, to ground. As soon as the commutator brush 232 engages the first conducting segment of the commutator 237, a circuit is closed from 75 grounded battery, upper contacts of sequence switch spring 201, contact 227, winding of relay 202, lower right-hand contact of sequence switch spring 230, left-hand armature and front contact of relay 202, upper 80 and lower right-hand contacts of sequence switch spring 203, conductor 238, conducting segment of commutator 237, brush 232, lower right-hand contact of sequence switch spring 220, to ground. This circuit shunts 85 out the stepping relay 494, which in turn causes the energization of the 0' counting relay in the same manner as previously described. The 0' counting relay by attracting its inner armature completes a circuit 90 from grounded battery, power magnet of sequence switch 490, inner armature and front contact of 0' counting relay, left-hand contact of sequence switch spring 485, to ground, for moving sequence switch 490 out of position 95 10 and into position 12. The 0' counting relay by attracting its outer armature opens the fundamental circuit, thereby allowing the relay 202 to deenergize as soon as the commutator brush 232 engages an insulated 100 segment of the commutator 237. Relay 202 by retracting its right-hand armature opens the energizing circuit of the updrive magnet 217 and closes a circuit from grounded battery, power magnet of sequence switch 200, 105 upper right-hand contact of sequence switch spring 211, back contact and right-hand armature of relay 202, to ground, for moving the sequence switch 200 out of position 4 and into position 5. The brushes 223, 224 110 and 225 are now in engagement with the first set of terminals in the selected group.

In position 5 of sequence switch 200 a circuit is closed from grounded battery, lower contact of sequence switch spring 218, left-hand winding of relay 219, upper and lower right-hand contacts of sequence switch spring 220, to ground. Relay 219 by attracting its left-hand armature closes a circuit from 115 grounded battery, power magnet of sequence switch 200, upper contact of sequence switch spring 239, left-hand armature and front contact of relay 219, to ground, for moving the sequence switch 200 out of position 5 and into position 6. If the brush 223 120 is in engagement with the terminal of a busy trunk, a circuit is now closed from grounded battery, right-hand winding of relay 219, lower contact of sequence switch spring 221, right-hand armature and front contact of 125 130

relay 219, resistance 222, brush 223, to ground, through the test terminal 241 of the busy trunk. Relay 219 is thereby held energized in position 6 and completes a circuit from grounded battery, winding of up-drive magnet 217, upper contact of sequence switch spring 213, left-hand armature and front contact of relay 219 to ground. Under the control of the updrive magnet 217, the 5 brushes are moved upward over the contacts of the selected group of trunks until the test brush 223 engages the test terminal of an idle trunk, at which time the relay 219 deenergizes, due to the absence of ground 10 on the test terminal. Relay 219 is held energized, however, until the brushes are accurately centered on the terminals of the idle trunk, due to a circuit being closed from grounded battery, lower contact of sequence 15 switch spring 218, left-hand winding of relay 219, conducting segment of commutator 240, commutator brush 234, lower left-hand contact of sequence switch spring 220, left-hand armature and front contact of relay 219, to ground. As soon as the brushes are 20 accurately centered on the terminals of the idle trunk, the commutator brush 234 engages an insulated segment of the commutator 240, thus causing the deenergization of 25 relay 219. Relay 219 by retracting its left-hand armature opens the circuit of the up-drive magnet 217 and closes a circuit from 30 grounded battery, power magnet of sequence switch 200, lower contacts of sequence switch spring 214, left-hand armature and back contact of relay 219 to ground, for moving the sequence switch 200 out of position 6 and into position 7. As soon as the sequence 35 switch reaches position 6-3/4, ground is connected to the test terminal 241 of the selected trunk and causes this trunk to test busy, this circuit being traced from test terminal 241, brush 223, resistance 222, lower contact of sequence switch spring 244, to 40 ground.

In position 7, a circuit is closed from 45 grounded battery, upper contacts of sequence switch spring 201, contact 227, winding of relay 202, left-hand contact of sequence switch spring 230 to ground. Relay 202 by attracting its right-hand armature completes a circuit from grounded battery, power magnet of sequence switch 200, upper left-hand contact of sequence switch spring 50 211, right-hand armature and front contact of relay 202, to ground, for moving sequence switch 200 out of position 7 and into position 9. Relay 202 by attracting its left-hand armature completes a locking circuit 55 for itself, this circuit being traced from grounded battery, upper contacts of sequence switch spring 201, contact 227, winding of relay 202, right-hand contact of sequence switch spring 230, left-hand armature and front contact of relay 202, con-

ductor 246, right-hand contact of sequence switch spring 247, conductor 248, brush 224, terminal 242, conductor 301, lower left-hand and upper right-hand contacts of sequence switch spring 302, resistance 303, to ground. Relay 202 is held energized over this circuit until the sequence switch 300 leaves position 6.

As soon as the sequence switch 200 reaches position 9 and the sequence switch 490 reaches position 12, a circuit is completed from grounded battery, winding of relay 304, lower left-hand contact of sequence switch spring 305, conductor 306, terminal 243, brush 225, conductor 249, upper left-hand contact of sequence switch spring 250, resistance 228, over the fundamental circuit previously described, to ground, through the resistance 207 and the contact of sequence switch spring 251. Relays 304 and 494 become energized. Relay 494 completes a circuit from grounded battery, winding of counting relay No. 2, armature and back contact of counting relay No. 2', conductor 489, No. 2 key of the hundreds row, lower left-hand contact of sequence switch spring 495, armature and front contact of relay 494, to ground. Counting relay No. 2 becomes energized and closes a circuit for counting relay No. 2' in the same manner as above described.

Relay 304 by attracting its right-hand armature closes a locking circuit for itself from grounded battery, winding of relay 304, right-hand armature and front contact of relay 304, lower right-hand contact of sequence switch spring 305, to ground, over the fundamental circuit. Relay 304 by attracting its left-hand armature completes a circuit from grounded battery, winding of relay 307, lower left-hand and upper right-hand contacts of sequence switch spring 308, left-hand armature and front contact of relay 304 to ground. Relay 307 by attracting its right-hand armature completes a locking circuit for itself from grounded battery, winding of relay 307, right-hand armature and front contact of relay 307, resistance 309, conductor 310, terminal 241, brush 223, resistance 222, lower contact of sequence switch 244, to ground. Relay 307 by attracting its left-hand armature closes a circuit from grounded battery, power magnet of sequence switch 300, upper right-hand contact of sequence switch spring 311, left-hand armature and front contact of relay 307, to ground, for moving the sequence switch 300 out of position 1 and into position 2.

In position 2 a circuit is completed from 125 grounded battery, winding of updrive magnet 312, lower contact of sequence switch spring 313, conductor 314, left-hand armature and front contact of relay 304, to ground. Under the control of the updrive 130

- magnet 312 the line brush sets 315, 316 and 317, the commutator brushes 318, 319 and 320 are moved upward. As soon as the commutator brush 319 engages the first conducting segment of the commutator 321, a circuit is completed from grounded battery, winding of relay 304, right-hand armature and front contact of relay 304, lower right-hand contact of sequence switch spring 305, 5 upper contact of sequence switch spring 322, conducting segment of commutator 321, commutator brush 319, lower contact of sequence switch spring 323, to ground. This circuit shunts out the stepping relay 494, 10 which deenergizes, and causes the energization of counting relay 2' in the same manner as above described. The brushes continue to move upward until the counting relay 0' is energized, at which time the 15 fundamental circuit is opened. Relay 304 then becomes deenergized as soon as the commutator 319 engages an insulated segment of the commutator 321. Relay 304 by retracting its left-hand armature opens the 20 circuit of the updrive magnet 312 and completes a circuit from grounded battery, power magnet of sequence switch 300, lower right-hand and upper left-hand contacts of sequence switch spring 308, left-hand armature and back contact of relay 304, to ground, for moving the sequence switch 300 out of position 2 and into position 3. The energization of counting relay 0' also completes a circuit from grounded battery, 25 power magnet of sequence switch 490, inner armature and front contact of counting relay 0', left-hand contact of sequence switch spring 485, to ground, for moving the sequence switch 490 out of position 12 and 30 into position 14. 35 As soon as the sequence switch 300 reaches position 3 and the sequence switch 490 reaches position 14, the fundamental circuit is again established, causing the energization of relays 304 and 494. Relay 494 by attracting its armature completes a circuit from grounded battery, winding of counting relay 1, armature and back contact of counting relay 1', conductor 487, No. 1 key of the 40 tens row, lower right-hand contact of sequence switch spring 495, armature and front contact of relay 494, to ground. Counting relay No. 1, by attracting its armature, closes a circuit through counting relay No. 1', in the same manner as above described. 45 Relay 304 by attracting its right-hand armature closes the locking circuit for itself as previously described, and by attracting its left-hand armature closes a circuit from grounded battery, sequence switch 300, lower and upper right-hand contacts of sequence switch 308, left-hand armature and front contact of relay 304, to ground, for moving the sequence switch 300 out of position 3 and 50 into position 4, and as soon as sequence switch 300 leaves position 4, the circuit of the updrive magnet 312 is closed, as previously described. Under the control of the updrive magnet 312, the brushes are again moved upward. The third set of brushes is 55 tripped at this time, since the trip magnet 324 is energized due to a circuit closed from grounded battery, winding of trip magnet 324, contact of sequence switch spring 325, to ground. As soon as the commutator brush 320 engages the first conducting segment of commutator 327, a circuit is closed from grounded battery, winding of relay 304, right-hand armature and front contact of relay 304, lower right-hand contact of sequence switch spring 305, lower contact of sequence switch spring 322, conducting segment of commutator 327, commutator brush 320, lower contact of sequence switch spring 323, to ground. This circuit closes a shunt 60 around the stepping relay 494, which deenergizes and allows the counting relay 1' to energize. As the brushes move upward the counting relays are actuated in the same manner as above described, and until the 65 counting relay 0' is again energized. Counting relay 0' by attracting its inner armature completes a circuit from grounded battery, power magnet of sequence switch 490, inner armature and front contact of counting relay 0', left-hand contact of sequence switch spring 485, to ground, for moving the sequence switch 490 out of position 14 and into position 16. Counting relay 0' by attracting 70 its outer armature again opens the fundamental circuit, thereby causing the deenergization of relay 304, as soon as the commutator brush 320 engages an insulated segment of commutator 327. Relay 304 by retracting its left-hand armature opens the 75 circuit of the updrive magnet 312, and closes a circuit from grounded battery, power magnet of sequence switch 300, lower right-hand and upper left-hand contacts of sequence switch spring 308, left-hand armature and back contact of relay 304, to ground, for moving the sequence switch 300 out of position 4 and into position 5. 80 As soon as the sequence switch 300 reaches position 5 and the sequence switch 490 reaches position 16, the fundamental circuit is again established, causing the energization of relays 304 and 494. Relay 494 by attracting its armature completes a circuit from grounded battery, winding of counting relay 2, armature and back contact of counting relay 2', conductor 486, No. 2 key of the units row, upper contact of sequence switch spring 495, armature and front contact of relay 494, to ground. Counting relay No. 2 by attracting its armature closes a circuit for counting relay No. 2', in the same manner as above described. Relay 304 by attracting its right-hand armature closes the locking circuit for itself, previ- 85 90 95 100 105 110 115 120 125 130

ously described, and by attracting its left-hand armature completes a circuit for moving the sequence switch 300 out of position 5 and into position 6, and as soon as the sequence switch reaches position 6 a circuit is closed from grounded battery, winding of slow-speed updrive magnet 328, upper contact of sequence switch spring 313, left-hand armature and front contact of relay 304, to ground. Under the control of magnet 328, the selected brush set is moved upward. As the brushes move upward, the brush 319 by engaging the commutator 321, actuates the counting relays in the same manner as above described. As soon as the counting relay 0' is energized, a circuit is completed from grounded battery, power magnet of sequence switch 490, inner armature and front contact of counting relay 0', left-hand contact of sequence switch spring 485, to ground, for moving the sequence switch 490 out of position 16 and into position 1. As soon as the sequence switch 490 reaches position 1, a circuit is closed from grounded battery, power magnet of sequence switch 100, lower contact of sequence switch spring 107, conductor 134, terminal 431, brush 432, contact of sequence switch spring 433, upper contact of sequence switch spring 484, to ground, for moving the sequence switch 100 out of position 11 and into position 16.

In position 1 of sequence switch 490, a circuit is also closed from grounded battery, winding of downdrive magnet 428 of the cord finder, contact of sequence switch spring 429, contact of sequence switch spring 483, to ground. Under the control of the down-drive magnet 428, the brushes of the cord finder are returned to their normal position. As soon as the commutator brush 417 reaches its normal position, a circuit is closed from grounded battery, power magnet of sequence switch 400, lower right-hand contact of sequence switch spring 404, conductor 430, conducting segment 451, commutator brush 417, to ground, for moving the sequence switch 400 out of position 8 and into position 1.

When the fundamental circuit was opened by the energization of counting relay 0', relay 304 became deenergized as soon as the commutator brush 319 engaged an insulated segment of the commutator 321. Relay 304 by retracting its left-hand armature opens the circuit of the updrive magnet 328 and closes a circuit from grounded battery, power magnet of sequence switch 300, lower right-hand and upper left-hand contacts of sequence switch spring 308, left-hand armature and back contact of relay 304, to ground, for moving the sequence switch 300 out of position 6 and into position 7. The brushes 315, 316 and 317 are now in engagement with the terminals of the desired line.

As soon as the sequence switch 300 leaves

position 6, the holding circuit of relay 202 is opened at the upper right-hand contact of sequence switch spring 302. The deenergization of relay 202 closes a circuit from grounded battery, power magnet of sequence switch 200, upper right-hand contact of sequence switch spring 211, right-hand armature and back contact of relay 202, to ground, for moving the sequence switch 200 out of position 9 and into position 10. A circuit is now closed from grounded battery, lower left-hand contact of sequence switch spring 252, winding of relay 253, upper left-hand winding of repeating coil 254, conductor 205, terminal 131, brush 117, upper contact of sequence switch spring 132, upper right-hand winding of repeating coil 135, to ground. Relay 253 closes a locking circuit for itself from grounded battery, left-hand contact of sequence switch spring 252, winding of relay 253, lower contact of sequence switch spring 255, armature and front contact of relay 253, conductor 256, upper contact of sequence switch spring 218, left-hand winding of relay 219, upper and lower right-hand contacts of sequence switch spring 220, to ground. Relay 219 becomes energized and closes a locking circuit for itself from grounded battery, right-hand winding of relay 219, lower contact of sequence switch spring 221, right-hand armature and front contact of relay 219, lower contact of sequence switch spring 244 to ground. Relay 219 also closes a circuit from grounded battery, lower contact of sequence switch spring 258, winding of relay 259, right-hand armature and front contact of relay 219, lower contact of sequence switch spring 244, to ground. Relay 259 completes a circuit from grounded battery, resistance 262, left-hand armature and front contact of relay 259, winding of relay 202, lower left-hand contact of sequence switch spring 230, to ground. Relay 202 becomes energized and completes a circuit from grounded battery, power magnet of sequence switch 200, upper left-hand contact of sequence switch spring 211, right-hand armature and front contact of relay 202, to ground, for moving the sequence switch 200 out of position 10 and into position 12.

As soon as sequence switches 200 and 300 reach positions 11 and 7, respectively, a circuit is closed from grounded battery, winding of relay 304, lower left-hand contact of sequence switch spring 305, conductor 306, terminal 243, brush 225, conductor 249, lower contact of sequence switch spring 250, upper armature and back contact of relay 260, upper right-hand winding of repeating coil 254, to ground. Relay 304 by attracting its left-hand armature completes a circuit for moving the sequence switch 300 out of position 7 and into position 8, this circuit being traced from grounded battery, power

magnet of sequence switch 300, lower and upper right-hand contacts of sequence switch spring 308, left-hand armature and front contact of relay 304, to ground.

5 It will first be assumed that the called line is idle and a high battery potential will then be found upon the test terminal 328. As soon as the sequence switch 300 reaches position 8, a circuit is closed from 70
10 grounded battery, winding of cutoff relay 331, terminal 328, brush 315, contact of sequence switch spring 332, left-hand low resistance winding of relay 333, lower contacts of sequence switch spring 334, right-
15 hand high resistance winding of relay 333, to ground. Relay 333 becomes energized and completes a locking circuit for itself, this circuit being traced through its left-hand low resistance winding and its left-
20 hand armature and front contact, to ground. This circuit shunts out the high resistance of winding of relay 333 and so reduces the potential on the terminal 328 as to cause the line to test busy. The energization of
25 relay 333 also closes a circuit from grounded battery, power magnet of sequence switch 300, lower left-hand contact of sequence switch spring 311, right-hand armature and front contact of relay 333, to ground, for
30 moving the sequence switch 300 out of position 8 and into position 10. As soon as the sequence switch 300 leaves position 7-1/4, the relay 304 deenergizes so that the sequence switch 300 is immediately moved
35 out of position 10 and into position 14, due to a circuit being closed from grounded battery, power magnet of sequence switch 300, lower right-hand and upper left-hand contacts of sequence switch spring 308, left-
40 hand armature and back contact of relay 304, to ground. Sequence switch 300 is moved out of position 14 and into position 16, due to the circuit previously described, for moving it out of position 8. In position
45 16, the line conductors 306 and 301 are extended through to the called line.

As soon as the sequence switch 200 reaches position 11 when moving from position 10 to position 12 in the manner above described, the relay 253 is held energized over a circuit traceable from grounded battery, upper contact of sequence switch spring 261, left-hand armature and front contact of relay 202, lower right-hand contact of sequence switch spring 252, winding of relay 253, upper left-hand winding of repeating coil 254, conductor 205, terminal 131, brush 117, upper contact of sequence switch spring 132, upper right-hand winding of repeating coil 135 to ground. In position 11, the relay 253 completes a circuit from grounded battery, upper contact of sequence switch spring 255, armature and front contact of relay 253, upper contact of sequence switch spring 258, winding of relay 259, upper

left-hand contact of sequence switch spring 244, to ground. This circuit is maintained energized until the sequence switch 200 leaves position 14. Relay 259, by holding its left-hand armature attracted, still maintains the circuit for relay 202 closed. 70

It will be assumed that the commutator brush 233 is in engagement with an insulated segment of the commutator 263, when the sequence switch 200 reaches position 12. 75
A circuit will then be closed from grounded battery, upper contact of sequence switch spring 255, armature and front contact of relay 253, upper contacts of sequence switch spring 258, winding of relay 260, armature and back contact of relay 264, armature and back contact of relay 265, left-hand armature and back contact of relay 219, to ground. Relay 260 becomes energized and connects ringing current to the called line over a 80 circuit from grounded source of ringing current, left-hand winding of relay 265, left-hand contact of sequence switch spring 266, lower armature and front contact of relay 260, left-hand contact of sequence switch spring 247, conductor 248, brush 224, terminal 242, conductor 301, lower contacts of sequence switch spring 302, brush 316, terminal 329, apparatus of substation B, terminal 330, brush 317, upper contact of sequence switch spring 305, conductor 306, terminal 243, brush 225, conductor 249, lower contact of sequence switch spring 250, upper armature and front contact of relay 260, to ground. 90
95

100 Relay 265 does not become energized at this time due to the high resistance in the circuit at the substation B. Ringing current is thus applied to the called line until the called party answers, at which time relay 265 receives sufficient current and attracts the armature. A circuit is then closed through the winding of relay 264, which had previously been shunted out by the circuit through the armature and back contact of relay 265 and the armature and back contact of the relay 264. Relay 264 by attracting its armature closes a locking circuit for itself and places a shunt around relay 260. Relay 260 deenergizes and connects the subscribers' lines together for conversation. 105
110

115 The operator now depresses the listening out key 179, provided she has not previously done so, which completes a circuit from grounded battery, power magnet of sequence switch 175, upper contact of sequence switch spring 177, key 179 to ground, for moving the sequence switch 175 into position 8, which is the listening out position. 120
125

As soon as the subscribers are through talking and have replaced their receivers, the operator receives a disconnect signal in the well-known manner. She then removes plug 104 from jack 105. Relay 106 deener- 130

gizes and completes a circuit from ground-
ed battery, power magnet of sequence switch
175, lower contact of sequence switch
spring 177, armature and back contact of
5 relay 106 to ground, for moving the se-
quence switch 175 out of position 8 and into
position 1.

The deenergization of relay 106 also closes
10 a circuit from grounded battery, power mag-
net of sequence switch 100, upper right-hand
contact of sequence switch spring 107, arma-
ture and back contact of relay 106 to ground,
for moving the sequence switch 100 out of
15 position 16 and into position 18. In pos-
ition 18, a circuit is completed from ground-
ed battery, winding of downdrive magnet
138, lower contact of sequence switch spring
112 to ground. Under the control of the
20 downdrive magnet 138, the brush rod 116 is
returned to its normal position. As soon
as the commutator brush 120 reaches its nor-
mal position, a circuit is completed from
25 grounded battery, power magnet of sequence
switch 100, upper right-hand contact of se-
quence switch spring 113, conducting seg-
ment 139, commutator brush 120 to ground,
for moving the sequence switch 100 out of
30 position 18 and into position 1.

As soon as the sequence switch 100 leaves
30 position 16, the holding circuit of relay 253
is opened at the upper left-hand contact
of sequence switch spring 132. Relay 253
by retracting its armature opens the circuit
35 of relay 259, which deenergizes, and opens
the circuit of relay 202. Relay 202 by re-
tracting its right-hand armature closes a
circuit from grounded battery, power mag-
net of sequence switch 200, upper right-hand
40 contact of sequence switch spring 211, right-
hand armature and back contact of relay
202 to ground, moving the sequence switch
out of position 12 through position 14 and
into position 18. In position 18, a circuit is
45 completed from grounded battery, winding
of downdrive magnet 271, lower contact of
sequence switch spring 215 to ground. Under
the control of the downdrive magnet
217, the brush rod 236 is returned to its nor-
50 mal position. As soon as the commutator
brush 234 reaches its normal position, a cir-
cuit is completed from grounded battery,
power magnet of sequence switch 200, lower
55 contact of sequence switch spring 275, con-
ducting segment 276, commutator brush 234,
lower contact of sequence switch spring 220
to ground, for moving the sequence switch
200 out of position 18 and into position 1.

As soon as the sequence switch 200 leaves
60 position 16, the holding circuit of relay 307
is opened at the lower contact of the sequence
switch spring 244. Relay 307 by retracting
its left-hand armature completes a circuit
from grounded battery, power magnet of
65 sequence switch 300, upper left-hand contact

of sequence switch 311, left-hand armature 65
and back contact of relay 307 to ground, for
moving the sequence switch out of position
16, through position 17 and into position 18.
A circuit is then closed from grounded bat-
tery, winding of downdrive magnet 340, 70
lower contact of sequence switch spring 341
to ground. Under control of the downdrive
magnet 340, the brush rod 342 is returned to
its normal position. As soon as the com-
mutator brush 320 reaches its normal pos-
75 ition, a circuit is completed from grounded
battery, power magnet of sequence switch
300, lower right-hand contact of sequence
switch spring 311, conductor 344, conducting
segment 343, commutator brush 320, lower 80
contact of sequence switch spring 323 to
ground, for moving the sequence switch 300
out of position 18 and into position 1.

If the called line is busy when the se-
quence switch 300 reaches position 8, the 85
test relay 333 does not receive sufficient cur-
rent to attract its armatures, due to the low
potential on the test terminal 328. Relay
304, however, is energized in this case in
position 8, due to a circuit being closed 90
from grounded battery, winding of relay
304, lower contacts of sequence switch spring
337, left-hand armature and back contact
of relay 338, right-hand armature and back
contact of relay 333 to ground. Relay 304 95
by attracting its left-hand armature com-
pletes a circuit from grounded battery,
power magnet of sequence switch 300, lower
and upper right-hand contacts of sequence
switch spring 308, left-hand armature and
100 front contact of relay 304 to ground, for
moving the sequence switch 300 out of posi-
tion 8 and into position 10. As soon as the
sequence switch reaches position 9, a circuit
is closed from grounded battery, winding of 105
relay 338, upper contacts of sequence switch
spring 339 to ground. The energization of
relay 338 opens the circuit of relay 304,
which deenergizes and completes a circuit
110 for moving the sequence switch 300 out of
position 10 and into position 14, this circuit
being traced from grounded battery, power
magnet of sequence switch 300, lower right-
hand and upper left-hand contacts of se-
115 quence switch spring 308, left-hand armature
and back contact of relay 304 to ground. In
position 14, a circuit is completed for the
downdrive magnet 340, from grounded bat-
tery, winding of downdrive magnet 340, up-
120 per contact of sequence switch spring 341,
right-hand armature and back contact of re-
lay 333 to ground. Under the control of
the downdrive magnet 340, the brush shaft
342 is returned to its normal position. As
soon as the commutator brush 320 engages
125 the normal conducting segment 343, a cir-
cuit is closed from grounded battery, power
magnet of sequence switch 300, lower right-

hand contact of sequence switch spring 311, conductor 344, conducting segment 343, brush 320, lower contact of sequence switch spring 323 to ground, for moving the sequence switch 300 out of position 14 and into position 17. A busy tone is now connected to the lower line conductor 301 through the upper contacts of sequence switch spring 334. The operator receives a 5 characteristic flash of the so-called supervisory lamp (not shown) in a well-known manner and removes plug 104 from the jack 105, thereby causing the deenergization of relay 106. The switches are then returned to their 10 normal positions in the same manner as above described.

We will now consider the wipe-out operation which may take place in position 11 of sequence switch 100. It will be remembered that the sequence switch 400 is in position 8 at this time. It will also be observed that the wipe-out operation can only take place while the sequence switch 175 is in position 5. When the wipe-out key 173 is 15 operated, a circuit is completed from grounded battery, winding of relay 140, upper contact of sequence switch spring 174, wipe-out key 173 to ground. In position 11 of the sequence switch 100, relay 140 completes 20 a circuit from grounded battery, winding of relay 421, brush 440, terminal 441, conductor 442, contact of sequence switch spring 144, armature and front contact of relay 140 to ground. Relay 421 by 25 attracting its left-hand armature completes a locking circuit for itself from grounded battery, winding of relay 421, left-hand armature and front contact of relay 421, upper contact of sequence switch spring 435, lower 30 contact of sequence switch spring 484 to ground. Relay 421 by attracting its right-hand armature opens the fundamental circuit through the stepping relay 494 and closes it through the right-hand winding of 35 the relay 436. In this manner the switch being operated is removed from the control of the counting relays. Assuming that the brushes 117, 118 and 119 have just engaged the terminals 131, 130 and 127, respectively, 40 at the time the wipe-out key 173 is operated. Sequence switch 200 will move into position 2 in the same manner as above described, causing the fundamental circuit to be closed in the same manner as above described except 45 that it will be completed through the right-hand winding of relay 436 instead of through the winding of stepping relay 494 and the outer armature and back contact of the counting relay 0'. Relay 436 will not, 50 however, be energized at this time due to the high resistance of the winding 202. In position 2 of the sequence switch 200, the above traced circuit of the updrive magnet 217 will be completed. Under the control

of this updrive magnet, the brush rod 236 65 will be moved upward until the commutator brush 234 engages the overflow segment 277. As soon as the commutator brush 234 engages the overflow contact 277, a circuit is completed from grounded battery, power 70 magnet of sequence switch 200, upper contact of sequence switch spring 275, overflow contact 277, commutator brush 234, lower contact of sequence switch spring 220 to ground, for moving the sequence switch out 75 of position 2, through positions 3, 4 and 5 and into position 6. The sequence switch 200 is moved out of position 6 and into position 7, due to a circuit being closed from grounded battery, power magnet of sequence 80 switch 200, lower contacts of sequence switch spring 214, left-hand armature and back contact of relay 219 to ground. The sequence switch 200 is moved out of position 7 through positions 8 and 9 and into position 85 10, due to the circuit above described for moving it out of position 2. In position 10, a circuit is completed from grounded battery, lower contact of sequence switch spring 208, winding of relay 209, upper contact of 90 sequence switch spring 210, over-flow contact 277, commutator brush 234, lower contact of sequence switch spring 220 to ground. Relay 209 completes a circuit from grounded battery, left-hand contact of sequence switch 95 spring 252, winding of relay 253, upper left-hand winding of repeating coil 254, conductor 205, terminal 131, brush 117, lower contact of sequence switch spring 132, conductor 111, terminal 419, brush 420, right-hand armature and front contact of relay 421, right-hand winding of relay 436, brush 422, terminal 423, conductor 424, upper contact of sequence switch spring 133, brush 118, terminal 130, conductor 206, upper contact of sequence switch spring 279, armature and front contact of relay 209, lower contact of sequence switch spring 212 to ground. Relay 436 now receives sufficient current to 100 attract its armatures and completes a locking circuit for itself from grounded battery, left-hand winding of relay 436, left-hand armature and front contact of relay 436, lower contact of sequence switch spring 435, lower contact of sequence switch spring 484 to ground. Relay 436 also completes a circuit from grounded battery, power magnet of sequence switch 490, upper left-hand contact of sequence switch spring 492, right-hand armature and front contact of relay 436 to ground, for moving the sequence switch 490 into its normal position. As soon as the sequence switch 490 reaches position 1, the cord finder is released and the sequence switch 100 moved into position 16 110 115 120 125 in the same manner as above described.

The energization of relay 253 causes the sequence switch 200 to move into position 12

in the same manner as above described. As soon as the operator removes the plug 104 from the jack 105, the sequence switches 100 and 200 are moved into their normal positions in the same manner as above described.

If the wipe-out key is operated while the sequence switch 200 is in position 3, it continues to operate in the same manner as described for usual operation, until it reaches position 4. In position 4, brush shaft 236 is moved upward to its overflow position in the same manner as when the wipe-out key was operated in position 2 of the sequence switch 200. The cord finder, district and incoming selectors are then released in the same manner as just described. If the wipe-out key is depressed after the sequence switch 200 leaves position 4, an idle trunk leading to a final selector is seized in the same manner as above described and the fundamental circuit is completed, causing the energization of relay 304 which moves the sequence switch 300 into position 2. The relay 436 does not attract its armatures at this time, due to the high resistances of the winding of relay 304, and of the resistance 303. Due to the energization of relay 304, the circuit for the updrive magnet 312 will be closed, thereby causing the brushes to move upward until the commutator brush 320 engages the overflow contact 350. A circuit is then completed from grounded battery, power magnet of sequence switch 300, lower right-hand contact of sequence switch spring 351, overflow contact 350, commutator brush 320, lower contact of sequence switch spring 323 to ground, for moving the sequence switch out of position 2 and into position 10. As soon as the sequence switch 300 leaves position 6, the sequence switch 200 is moved out of position 9 and into position 10 in the manner above described. Relay 304 is deenergized in position 10 in the same manner as above described, so that the sequence switch 300 is immediately moved out of position 10 and into position 14, due to a circuit from grounded battery, power magnet of sequence switch 300, lower right and upper left-hand contacts of sequence switch spring 308, left-hand armature and back contact of relay 304 to ground. Sequence switch 300 is immediately moved out of position 14 and into position 16, due to the circuit which moved it out of position 2. As soon as the sequence switch 300 reaches position 16, a circuit is closed for the relay 209, from grounded battery, lower contact of sequence switch spring 208, winding of relay 209, upper contact of sequence switch spring 210, upper right-hand contact of sequence switch spring 250, conductor 249, brush 225, terminal 243, conductor 306, lower right-hand contact of sequence switch spring 305, lower left-hand contact of sequence

switch spring 351, overflow contact 350, commutator brush 320, lower contact of sequence switch spring 323 to ground. Relay 209 by attracting its armature completes the above described circuit for energizing the relay 436, whereupon the cord finder, district, incoming and final selectors are released in the manner above described. If the wipe-out key is depressed while the sequence switch 300 is in position between 2 and 7, it is obvious that the brushes of the final selector will be moved upward until the overflow contact is reached, whereupon the connection will be released in the manner similar to that just described.

What is claimed is:

1. In a telephone exchange system, a switch, sending apparatus, means to operate said switch in a motion controlled by said sending apparatus, means operative during said motion to render said sender control ineffective and to allow said motion to continue until a limiting position is reached, and means made operative when said limiting position is reached for releasing said switch.

2. In a telephone exchange system, a train of switches, sending apparatus, means to operate each of said switches in a motion controlled by said sending apparatus, means operative during any one of said motions to render said sender control ineffective and to allow the motion of the switch being operated to continue until a limiting position is reached, and means made operative when said limiting position is reached for releasing said switch and the switches previously controlled by said sending apparatus.

3. In a telephone exchange system, a train of switches, sending apparatus, means to operate each of said switches in a motion controlled by said sending apparatus, a wipe-out key, means controlled by said key when operated during any one of said motions for rendering said sender control ineffective and to allow the motion of the switch being operated to continue until a limiting position is reached, and means made operative when said limiting position is reached for releasing said switch and the switches previously controlled by said sending apparatus.

4. In a telephone exchange system, a train of switches, a control circuit therefor, sending apparatus arranged to be included in said control circuit, means controlled by said circuit for operating each of said switches in a motion controlled by said sending apparatus, means operative during any one of said motions to disconnect said sending apparatus from said circuit and to maintain said circuit closed to allow the motion of the switch being operated to continue until a limiting position is reached, and means made operative when said limiting position is reached for releasing said switch and the

switches previously controlled by said sending apparatus.

5. In a telephone exchange system, a train of switches, a control circuit therefor, sending apparatus arranged to be included in said control circuit, means controlled by said circuit for operating each of said switches in a motion controlled by said sending apparatus, a marginal relay, a wipe-out key, a relay operative by the depression of said key during any one of said motions to disconnect said sending apparatus from said circuit and to maintain said control circuit closed to allow the motion of the switch being controlled to continue until a limiting position is reached, an energizing circuit for said marginal relay completed when said limiting position is reached, and means operative by said marginal relay energizing for releasing said switch and the switches previously controlled by said sending apparatus.
6. In a telephone system, a switch, a control circuit therefor, sending apparatus arranged to be included in said control circuit, means controlled by said circuit for operating said switch in a motion controlled by said sending apparatus, means operative during said motion for disconnecting said sending apparatus from said circuit and for

maintaining said circuit closed to allow said motion to continue until a limiting position is reached, and means made operative when said limiting position is reached for releasing said switch.

7. In a telephone exchange system, a calling line, a connecting circuit terminating in a selector switch, means for connecting said calling line to said connecting circuit, a called line, a plurality of switches, sending apparatus, means for operating each of said plurality of switches successively in a motion controlled by said sending apparatus to extend a connection from said selector switch to said called line, means operative during any one of said movements to render said sender control ineffective and to allow the motion of the switch being operated to continue until a limiting position is reached, and means made operative when said limiting position is reached for releasing the switch being operated and the switches previously controlled by said sending apparatus.

In witness whereof we hereunto subscribe our names this 22nd day of November, A. D. 55 1917.

ALBEN E. LUNDELL.
FRANKLIN A. STEARN.
